UNITED STATES PATENT OFFICE.

ALEXANDER LAUGHLIN, JR., OF EDGEWORTH, PENNSYLVANIA; MARGARET M. LAUGHLIN AND THE UNION TRUST CO. OF PITTSBURGH, EXECUTORS OF SAID ALEXANDER LAUGHLIN, JR., DECEASED, ASSIGNS TO CENTRAL TUBE COMPANY, OF PITTSBURGH, PENNSYLVANIA, A CORPORATION OF PENNSYLVANIA.

METHOD AND APPARATUS FOR MANUFACTURING TUBES.

Application filed November 15, 1923. Serial No. 674,845.

The present invention relates broadly to the manufacture of pipes or tubes, and more particularly to the art of manufacture of butt-welded tubes.

- 5 At the present time tubes of the character herein contemplated are manufactured by heating comparatively short strips of skelp to the required temperature and then gripping the same by a pair of tongs, slipping a
 10 bell over the tongs, and attaching the tongs to a suitable draw bench. The operation of the draw bench places the tube under a tremendous tension which, due to the temperature at which the material is worked, is de-
 15 cidedly objectionable. There is also a considerable amount of work involved in handling the bells and returning the tongs to the furnace for repeated use. Also the bells wear out gradually, thereby imparting a
 20 gradually decreasing pressure on the skelp and producing poor welds. Due also to the time required to bring a fresh strip up to welding temperature after each preceding tube has been formed, the operation is de-
 25 cidedly intermittent and the process necessary comparatively slow considered from a basis of the investment involved.

In accordance with the present invention there is provided an improved method and
 30 apparatus by means of which the output of a given furnace can be materially increased without materially increasing the furnace size and without adding any additional drawing or forming means.

35 In the accompanying drawings there is shown, for purposes of illustration only, certain embodiments of the present invention, it being understood that the drawings do not define the limits of the invention, as changes
 40 may obviously be made therein without departing from the spirit of the invention or scope of my broader claims.

In the drawings—

45 Figure 1 is a side elevation of one form of apparatus constructed in accordance with the present invention, the furnace being shown in vertical section;

Figure 1^a is a view, on a reduced scale, showing one form of delivery means;

50 Figure 2 is a horizontal sectional view on the line II—II of Figure 1, looking in the direction of the arrows; and

Figure 3 is a view similar to Figure 2, illus-

trating a modified form of apparatus constructed in accordance with my invention. 55

In carrying out the present invention there may be provided a furnace 2 of any desired construction adapted to be heated in any well known manner, as by fuel and air, supplied through ports 3, there being a stack 4 for the 60 offtake of the waste gases.

Provided within the furnace and projecting upwardly from the base thereof in substantially parallel relationship is a plurality of supports 5, preferably arranged in pairs. 65 Each pair of supports is adapted to receive thereon one or more shafts 6, each carrying a coil of strip material or skelp from which a tube is formed. These coils may be easily rolled into the furnace through a charging 70 opening 7 at the rear thereof and along the supports until the shafts engage the stops or abutments 8.

In the front wall of the furnace, substantially in alignment with each of the coils is 75 a drawing opening 9 through which the skelp may be withdrawn after it has been heated to the required temperature for passage to a roll forming and welding apparatus. If desired, a continuous drawing opening may 80 be provided. The drawing apparatus may conveniently comprise a frame 10 adapted to be moved transversely across the front of the furnace into successive positions to cooperate with different pieces of skelp. This movement of the frame 10 may be accomplished in any desired manner as, for example, by providing a pair of screws 11 suitably interconnected for rotation in unison and adapted to be driven by a motor 12. Carried by the 85 frame 10 is a plurality of shafts 13 having at their upper ends forming rolls 14, these rolls being arranged in pairs. It will be understood that the axes of the rolls may be parallel, as indicated in the drawings, or that 90 one or more pairs of rolls may have their axes at an angle to the axes of the other rolls. All of the shafts 13 may be intergeared for simultaneous rotation and may be driven in any desired manner, as by a motor 15 having 95 on its shaft 16 a driving gear 17 in operative engagement with the driven gear 18.

In operation a plurality of coils of material may be successively charged into the furnace at suitably timed intervals to insure the raising of the temperatures thereof to the desired 100 105

point successively at slightly different times. In this manner the coil first charged into the furnace may first be drawn outwardly and formed into a tube by the forming means the 5 rolls of which act successively to form the weld, and thereafter straighten or finish the tube to the required diameter. As soon as one coil has been formed into a tube, the motor 10 12 may be operated to move the forming means to the next position whereupon the second coil will be withdrawn. At the same time a fresh coil may be charged into the furnace to take the place of the one just uncoiled. In this manner a continuous supply 15 of coils may be maintained within the furnace so that the tube forming operation is made more nearly continuous.

The broad method of heating in a coil as herein disclosed is made the subject matter 20 of my copending application Serial No. 674,843, of even date herewith. As disclosed therein, I may, if desired, regulate the temperature within the furnace in such manner that the free edges of the coils are not brought 25 to a welding temperature. In this manner sticking of the successive convolutions of the coils is obviated. To raise these edges to the required temperature for welding, I may provide supplemental burners 19 in cooperative 30 relation to the drawing openings 9, or I may provide means for supplying a blast of a suitable gas containing oxygen through blast pipes 20, as more fully disclosed in the 35 patents to Moon et al., Nos. 1,026,103 and 1,026,275 of May 14, 1912, or both.

Cooperating with the forming means and adapted to receive the tubes as delivered therefrom is a guide 21 gradually converging toward its outer end to direct all of the 40 tubes delivered thereto, irrespective of the position of the forming means, to one or more pairs of sizing and straightening rolls 22. These rolls in turn may deliver to a cooling 45 rack 23 as understood in the art.

In Figure 3 of the drawings there is illustrated a slightly modified embodiment of the 50 invention in which the strips are heated in short flat lengths and successively withdrawn by a single forming means. In this form of my invention, characters of reference similar to those already utilized but having a prime affixed thereto, are used to designate parts corresponding to parts hereinbefore described in detail.

Heretofore the use of rolls in place of bells 55 and dies has not been considered feasible due to the difficulty of moving the end of a heated strip into position between the first pair of rolls. As the temperature of the 60 skelp at the time it is withdrawn from the furnace is but slightly below the melting point, any delay will result in burning or

melting the skelp. This has necessitated the use of tongs and bells with all the consequent extra labor involved. In order to obviate these objections, I pre-shape one end 65 S of each strip to provide a cross section substantially the same as the cross section of the first roll pass in the forming means. This enables the leading ends of the strips, 70 whether in flat or coil form to be quickly entered in the first roll pass, whereupon the rolls themselves produce the necessary movement of the skelp for forming the tube, without any strain such as inherent in the use 75 of a draw bench.

With either of the forms of my invention it will be apparent that a single roll frame 80 may be effectively utilized in a manner similar to the ordinary present day draw bench, but with a decrease in labor involved and an increase in output, particularly where the skelp is heated in coils.

The advantages of the present invention arise from the provision of a method and 85 apparatus by means of which a traversing roll frame may be effectively utilized for the formation of tubes.

I claim:

1. In the method of manufacturing butt 90 weld tubing, the steps comprising preshaping the ends of a plurality of pieces of strip so as to adapt the pieces to be initially gripped between forming rolls, charging the pieces of strip into a furnace in side-by-side relationship, heating them to bring the edges thereof to a welding temperature, and thereafter successively withdrawing the pieces of strip and welding the edges thereof to form butt weld tubing by the action of forming, 100 welding and feeding rolls operable about vertical axes, and charging a fresh piece of strip into the furnace to replace the withdrawn piece.

2. Apparatus for manufacturing tubes, 105 comprising a furnace adapted to support a plurality of pieces of skelp therein in side by side relationship, the furnace having a plurality of drawing openings through which the skelp may be withdrawn for formation 110 into tubes, roll forming, welding and feeding means comprising a plurality of pairs of rolls in cooperative relation to such opening, the axes of such rolls being vertical, and means producing a relative movement 115 between the furnace and the roll forming means for bringing the forming means successively into cooperative relation with different pieces of skelp, substantially as described.

In testimony whereof I have hereunto set 120 my hand.

ALEXANDER LAUGHLIN, JR.
